UNITED STATES PATENT OFFICE

WILFRED R. WOOD, OF LONDON, ENGLAND, ASSIGNOR TO INTERNATIONAL COMBUSTION ENGINEERING CORPORATION, OF NEW YORK, N. Y., A CORPORATION OF DELAWARE

STEAM GENERATOR

Application filed July 24, 1928. Serial No. 294,976.

This invention relates to certain improvements in steam generators and is particularly useful in boiler furnaces, i. e. in steam generators having furnace walls lined with 5 radiant heat steam evaporating tubes arranged to deliver their steam to a steam and water drum.

Owing to the rapid circulation in such radiant heat tubes and to their multiplicity 10 there is considerable turbulence in the steam and water drum which results in priming and consequent wet steam which is objectionable.

One of the objects of my invention is to 15 overcome this objection.

More specifically stated it is an object of my invention to provide drum means so constructed and arranged that the contents of such means is substantially segregated into portions whereby I am enabled to take off 20 dry steam from a portion in which objectionable turbulence does not take place.

Another object of my invention is to provide interconnected steam and water drums to which the steam generated under conditions 25 producing considerable turbulence is delivered and to provide such drums with chambers thru which the steam successively passes and to provide steam offtake means for a chamber or chambers in which no appreciable turbulence takes place.

How the foregoing together with such other objects and advantages as may hereinafter appear, or are incident to my invention, are 30 realized is illustrated in preferred form in the accompanying drawing, wherein:

The figure is a sectional elevation of a steam generator embodying my improvements.

I have illustrated my invention in connection 35 with a steam generator of the type in which the combustion space is largely defined by water tubes subject to radiant heat, it being understood that convection tubes may be additionally employed if desired. In such installations very rapid circulation is produced in the steam evaporating tubes owing to their multiplicity and to their being subject to radiant heat, and, in consequence, there is considerable turbulence in the steam and water space.

In the particular installation shown the combustion space A is defined by tubular side walls 2, 2, front and rear tubular walls, the rear wall 3 only appearing in the drawing, and the top or roof inclined tubular wall 4. A plurality of inclined tubes also extend across the bottom of the combustion space, it being preferable to arrange the bottom tubes in a bank as indicated at 5.

The side wall tubes are connected at their 60 lower ends into headers 6 and at their upper ends into headers 7, the lower headers 6 being connected into a lower header or drum of the front wall tubes (not shown) and the upper headers 7 being connected into the 65 steam and water drum 8. The rear wall tubes are connected at their lower ends into the drum 9 and at their upper ends into the steam and water drum 8. The roof tubes 4 are connected at one end into an upper header 70 or drum of the front wall tubes (not shown) and at the other end into the steam and water drum 8. The bank of tubes 5 are connected at one end into the lower drum of the front wall above mentioned and at the other end 75 into the drum 9.

A plurality of downcomer tubes 10 are provided for supplying water from the water space of the drum 8 to the lower drum of the front wall tubes. It will thus be seen that the 80 circulation in the water tubes of the wall and in the inclined tubes 4 and 5 is in an upward direction, the steam generated being delivered to the steam and water drum 8.

Fuel such as pulverized coal, is introduced 85 into the combustion chamber A by means of a plurality of burners 11 preferably located at the corners of the combustion chamber and disposed so as to deliver their streams tangentially to a circle having its centre in 90 the axial line of the chamber. Air, preferably preheated air, is introduced with the fuel as indicated at 12. The particular furnace illustrated is a down-draft one in which the violent swirling fuel and flame stream descends and sweeps over the tubes hereinbefore mentioned, the products of combustion 95 passing between the tubes of the bank of tubes 5 and passing to a rear outlet.

The steam and water drum 8 receives the 100

steam discharging from the tubes of the rear wall 3, the upper headers 7 of the side water walls, and the roof tubes 4. Due to the rapidity of circulation in the tubes there is a great deal of turbulence in the water space of the drum into which the tubes deliver, which turbulence, as above pointed out, gives rise to priming and results in there being a good deal of water with the steam in the steam space, in consequence of which troubles develop from wet steam if the steam is drawn directly from the steam space above the tubes in the usual manner.

I aim to overcome such difficulties by providing baffles 13 and 14 which divide the drum 8 into three communicating spaces or compartments *a*, *b* and *c*. The baffles are illustrated as being formed of a plurality of transverse plates arranged in louvre-like fashion, the spacing and inclination being such that steam passes from the space *b* to spaces *a* and *c* in a downward direction which causes a change in the direction of travel of the steam. These baffles are so arranged with respect to the headers 7, the roof tubes 4 and the tubes of the wall 3, that the turbulence hereinbefore mentioned is confined to the space *b* which is intermediate the end spaces *a* and *c*, there being no steam led to the end spaces other than that passing through the baffles.

Since there is no delivery of steam and water from the steam generating elements into the water spaces immediately beneath said end steam spaces, turbulence in the compartments *a* and *c* is very substantially less than in the intermediate compartment *b* and the steam having been subjected to a drying action by the change in direction, is very much drier in these end compartments.

Associated with the drum 8 and preferably located thereabove is a second drum 15 to which steam from the end chambers or compartments *a* and *c* of the drum 8 is led by means of pipes 16, 16, or other suitable connections. This drum 15 is also divided into communicating chambers or compartments, preferably three, which are designated by the reference letters *d*, *e* and *f*. The drum is divided into these compartments by means of the double baffles 17 and 18. The baffles in this instance each are formed of two rows of transverse plates arranged in louvre-like fashion.

The pipes or connections 16, 16 are connected from the end compartments *a* and *c* of the drum 8 into the end compartments *d* and *f* of the drum 15, there being no steam led to the intermediate compartment *e* other than that passing thru the baffles 17 and 18.

It is to be noted that the baffle plates 19 are oppositely inclined to the baffle plates 20, the inclination and spacing being such that the steam in passing from the end chambers to the intermediate chamber takes a double change

in direction which has the effect of further drying the steam.

The intermediate chamber *e* is provided with a steam outlet 21 which may be provided with a connection 22 for leading the dry steam from the chamber *e* to a superheater (not shown) or elsewhere.

Suitable downcomers are provided for the drum 15 and in this instance I have shown downcomers 23 for the intermediate chamber *e* and downcomers 24 for the end chambers *d* and *f*, the latter being connected into the pipes 16, 16. The downcomers are preferably connected into the same lower drum into which the downcomers 10 connect. As the various downcomers lead water to the evaporating tubes from spaces in which no great turbulence takes place effective water delivery is ensured.

From the foregoing it will be seen that I have provided an arrangement whereby defects in water tube boilers, particularly those employing radiant heat evaporating wall tubes, are effectively overcome.

What I claim is:—

1. In combination a steam and water drum, louvre-like means for dividing said drum into communicating compartments, a plurality of substantially upright radiant heat evaporating tubes discharging into at least one compartment of said drum, a second drum, louvre-like means for dividing said second drum into communicating compartments, means for establishing communication between at least one compartment of the second drum and at least one compartment of the first drum which does not directly receive the discharge of said tubes, and a steam outlet for at least one compartment of the second drum which is not directly in communication with the first drum. 90

2. The combination with a steam and water drum and a plurality of steam generating elements connected into said drum of louvre-like means for dividing the interior of said drum into end chambers and an intermediate chamber connecting with the end chambers, said intermediate chamber receiving the discharge of the generating elements, a second drum, louvre-like means for dividing the interior of said drum into end chambers and an intermediate chamber communicating with the end chambers, means for connecting the end chambers of the first drum to the end chambers of the second drum, and a steam outlet for the intermediate chamber of the second drum. 100

3. In combination a steam and water drum, a plurality of substantially upright radiant heat evaporating tubes, means for dividing the interior of said drum into communicating compartments, said tubes being connected to discharge into a compartment of the steam and water drum, a second drum, means for dividing the interior of said drum into com- 110

municating compartments, means for establishing communication between a compartment of the first drum other than the compartment receiving the discharge of said tubes and a compartment of the second drum, and a steam outlet for another compartment of the second drum, the dividing means for said drums including plate-like members arranged to cause the steam to change its direction in passing from one compartment to another.

In testimony whereof I have hereunto signed my name.

WILFRED R. WOOD.
